UNITED STATES PATENT OFFICE

MAXIMILIAN FÜBER, OF LUBECK, GERMANY, ASSIGNOR TO WILHELM KRAKOW, OF SCHLUTUP, NEAR LUBECK, GERMANY

DOORLOCK WITH MULTIPLE ACTION SPRING

Application filed April 8, 1931, Serial No. 528,687, and in Germany April 30, 1930.

This invention relates to a door lock, in which the latch bolt, roll back and bolt tumblers are acted upon by a common spring. The buffer spring employed is so arranged 5 that it exerts its full effect on the roll back, whereas it exerts a weaker effect on the latch bolt and bolt tumblers.

The invention consists in that a lever acting against the latch bolt forms an extension 10 of the bolt tumbler, the locking pin of the tumbler guided in the lock plate serving as pivot for the latch lever. At the point of transition between the bolt tumbler and the latch lever a plurality of supporting points 15 are provided for the common spring so that it acts according to its distance from the pivot point of the latch lever either more strongly on the latch lever or on the bolt tumbler.

20 An embodiment of the invention is illustrated by way of example in the accompanying drawing in which:

Fig. 1 shows the door lock in side elevation.

Fig. 2 shows the door lock with the lock 25 plate removed.

Fig. 3 is a rear end view of the lock.

The door lock, as in the ordinary furniture locks, is provided with a latch bolt *a*, having a longitudinal slot *b* for a guide pin *c* and 30 adapted to be reversed for doors closing to the right and to the left, a roll back *e* having a square hole *d* for the handle pin, the arm *f* of this roll back lying between the guide pin *c* and a bar *a'* mounted on the shank of the 35 latch bolt and a locking bolt *g* controlled by a slot guide *g'*. A pin *h* is provided on the roll back *e* for securing the buffer spring *i*, the other end of which is connected with the extension *l* of the bolt tumbler *l*, formed as 40 latch lever.

The lever *h* bearing against the end reinforcement of the latch bolt *a* is preferably made in one piece with the tumbler *l* for the bolt *g*, or is rigidly connected thereto. The 45 locking pin *m*, mounted in the tumbler *l* and which lies alternately in the notches *n*, *n'* of the bolt *g* and is guided in a slot *o* of the lock cover plate *p*, serves at the same time as pivot point for the latch lever *h*.

50 When the handle is turned, the spring *i* is

compressed by the turning roll back *e* and at the same time by the lever *h* forced back by the latch bolt *a* and turning around the locking pin *m*, whereas during the inward pressing of the latch bolt *a* by the keeper the spring 55 is only tensional from one end by the outwardly oscillating lever *h* (the position shown in dot-dash lines in Fig. 1).

The spring *i*, in order to act less strongly on the latch bolt *a* and the tumbler *l* than 60 on the handle roll back *e*, is arranged so that it acts at an angle to the direction of movement of the two locking elements *a* and *l* and consequently engages at the point of transition between the tumbler and the latch 65 lever. At this point of transition a plurality of supporting points *r* may be provided for the spring *i* so that it acts more strongly either on the latch lever *h* or on the bolt tumbler *l* according to its distance from the pivot *m* of the latch lever *h*.

When opening and closing the lock bolt *g*, the key bit *q* moves in the lower recess of the bolt and bears against the lower edge of the tumbler *l*. As it continues to turn, the key 75 bit *q* lifts the tumbler *l* compressing the spring *i*, so that the pin *m* moves upwards in the slot *o* until it is clear of the upper incision *n* or *n'* in the bolt *g* (the position shown in dot-dash lines in Fig. 2) and then 80 forces the bolt *g* forwards or backwards. During each movement of the tumbler *l* the lever *h* slides upwards on the latch bolt *a*, without however altering its action on this latter.

I claim:

1. A door lock including a latch bolt, a roll back for the latch bolt, a bolt tumbler having an extension forming a lever engaging the latch bolt, a locking bolt, and a locking pin 90 for the locking bolt carried by the bolt tumbler and guided for sliding movement into and out of locking engagement with the locking bolt, said pin forming a pivot for the bolt tumbler and lever.

2. A door lock including a latch bolt, a roll back for the latch bolt, a bolt tumbler having an extension forming a lever engaging the latch bolt, a locking bolt, a locking pin for the locking bolt carried by the bolt 100

tumbler and guided for sliding movement into and out of locking engagement with the locking bolt, said pin forming a pivot for the bolt tumbler and lever, and a single spring interposed between the tumbler and the roll back and urging the roll back to normal position with the latch bolt protracted and the tumbler into latch bolt protracting and locking bolt locking position.

3. A door lock including a latch bolt, a roll back for the latch bolt, a bolt tumbler having an extension forming a lever engaging the latch bolt, a locking bolt, a locking pin for the locking bolt carried by the bolt tumbler and guided for sliding movement into and out of locking engagement with the locking bolt, said pin forming a pivot for the bolt tumbler and lever, a single spring interposed between the tumbler and the roll back and urging the roll back to normal position with the latch bolt protracted and the tumbler into latch bolt protracting and locking bolt locking position, and a series of lugs projecting from the tumbler and forming means for selectively engaging the spring with the tumbler.

In the testimony whereof I affix my signature.

MAXIMILIAN FÜBER.
